EMERGENCY RELEASE FOR LOCKING
DEVICESIsaiah W. Vensel, Wilkinsburg, Pa., assignor to
Westinghouse Air Brake Company, a corpora-
tion of Pennsylvania

Application April 25, 1947, Serial No. 743,833

9 Claims. (Cl. 246—161)

1

My invention relates to emergency releases for locking devices, and particularly to emergency releases for locking devices having positive force-down features for a locking dog.

In railway signaling and traffic controlling systems use is often made of locking devices for enforcing certain restrictions upon the operation of elements of the systems. These locking devices comprise an operating member movable between a locking and an unlocking condition and operatively connected with a locking member for respectively moving that member into and out of locking engagement with a lockable member. Operation of the operating member between its locking and unlocking positions is controlled by a lock arrangement usually comprising a locking segment operatively connected with the operating member, and a locking dog movable into and out of locking engagement with the locking segment. The locking segment is provided with a shoulder which cooperates with the locking dog in its locking condition to prevent movement of the operating member from its locking to its unlocking position until such time as the locking dog is withdrawn from the path of movement of the shoulder. The locking dog is operated by any suitable means, such as by an electromagnet or by a mechanically operated time release mechanism, and in order to assure that the locking dog will be positioned in locking engagement with the segment, the locking segment is provided with a projection which cooperates with a depressor member connected with the locking dog for positively forcing down the locking dog into locking engagement with the segment when the operating member is operated from its unlocking to its locking position. The projection on the locking segment moves in conjunction with the segment and in a portion of the stroke of the segment engages a cammed surface formed on the depressor member to force that member downwardly so that its cammed surface is positioned beneath the projection. With the projection in this position, upward movement of the dog required to lift it out of the path of the segment shoulder will be limited by the engagement of the cammed surface of the member with the underside of the segment projection.

In normal operation the parts are arranged so that when the dog operating mechanism operates to withdraw the dog from the path of the shoulder, a suitable indication of this fact is displayed even though the dog is at that time retained in the path of the shoulder by the projection of the segment engaging the dog-carried depressing

2

member. When the operating member is moved through the first few degrees of rotation toward its unlocking position, the projection carried by the locking segment is moved clear of the depressor member, whereupon the operating mechanism immediately snaps the locking dog out of the path of the segment shoulder so that the operating member can be moved without interruption to its unlocking position merely by action of the operator in throwing the operating member after the unlocked indication has been displayed.

As is customary in devices of this character, means are required to provide for emergency release of the locking in the event of a failure of the dog operating mechanism to operate properly. It is desirable that the emergency release means provide for an operation similar to that obtained in normal operation, that is, that after effecting an emergency release and obtaining an indication of that condition, the operator will be able to throw the operating member to its unlocking position merely by acting upon the operating member alone. In such case, therefore, the emergency release must be effective when brought into play to establish a condition which remains unchanged during the course of operation of the operating member to its unlocking position.

It is an object of my invention to provide novel and improved emergency release means for locking devices incorporating positive force-down features for the locking dog, and which release means is arranged when brought into operation to establish a condition which remains unchanged throughout the operation of the operating member to its unlocking position.

Another object of my invention is to provide novel and improved means effective to provide an emergency release for locking devices arranged to permit operation of a locking dog to its unlocking position when the depressor member of the locking dog is in cooperating relation with a draw-down projection of the locking segment.

Another object of my invention is to provide a novel and improved emergency release for locking devices having positive force-down features for the locking dog.

Another object of my invention is to provide novel and improved means for obtaining emergency operation of locking devices.

The above-mentioned and other important objects and characteristic features of my invention are obtained by providing the locking device with a manually operable plunger arranged to

swing a pivoted depressor member of a locking dog out of engagement with a draw-down projection on the locking segment and subsequently to force the locking dog out of the path of movement of the locking segment shoulder.

Other important objects and features of my invention will be apparent from the following description.

I shall describe one form of apparatus embodying my invention and shall then point out the novel features thereof in claims.

Referring to the accompanying drawings, Fig. 1 is a front view with a portion broken away, showing one form of locking device provided with an emergency release embodying my invention. The portion broken away in Fig. 1 is shown in section taken on the line A—A of Fig. 3. Fig. 2 is a side view, partially in section, of the locking device illustrated in Fig. 1. Fig. 3 is a top view of the locking device shown in Fig. 1, with housing 60 and certain of the parts omitted. Fig. 4 is a partial view showing an arrangement of the parts which form a part of the locking device shown in the drawings. Fig. 5 is a side view showing an arrangement of some of the parts of the emergency release comprising my invention. Figs. 6 and 7 are side and end views, respectively, of the depressor member 41.

In each of the several views similar reference characters refer to similar parts.

Referring to the drawings, a locking device having positive force-down features for the locking dog and provided with an emergency release embodying my invention is represented, for example, in the form of the well-known tower indicator comprising a face plate 10, secured as by tap bolts 11 to a base 12. Plate 10 is provided with an opening 13 which aligns with an opening 14 provided in a supporting member 15 secured by bolts 16 to the base 12. An operating shaft 17 is mounted in the aligned openings 13 and 14 to project past the face plate 10 and has provided thereon an operating handle 18. A drum type circuit controller is provided for operating shaft 17 and comprises a plurality of contact bands 19 mounted on insulation carried by shaft 17, and which bands 19 cooperate with pairs of contact fingers 20 (see Fig. 4) secured by means of terminal posts 21 to insulation terminal blocks 22 which in turn are fastened by tap screws 23 to base plate 12. Shaft 17 is also provided with a crank arm 24 formed with an elongated slot 25 in which is mounted a driving pin 26 carried by a locking member 27. The locking member 27 as shown in Fig. 1 is adapted to be moved into and out of locking engagement with a lockable member 28, and when in locking engagement with member 28 projects into an opening 29 formed in member 28 to prevent movement of the latter member. Shaft 17 also is provided with a locking segment 30 having a notched or cut-away portion provided with a shoulder 31 which cooperates with a locking dog 32 pivotally mounted for movement into and out of the path of movement of shoulder 31.

The operation of dog 32 into and out of the path of shoulder 31 may be effected in any suitable manner commonly employed in locking devices of the type employed in railway signaling and traffic controlling systems. These means may, for example, comprise a time element device of the type shown in a copending application for Letters Patent of the United States Serial No. 734,273, filed March 12, 1947, by Kenneth J. J. McGowan, now Patent No. 2,520,848, dated August 29, 1950, for Locking Devices, or may as

shown comprise an electromagnet L having two cores 33, each surrounded by a magnetizing coil 34, mounted in parallel spaced relation on supporting member 15 and connected together at their lower ends by a back-strap 35. An armature 36 carried on an armature supporting member 37 pivoted on trunnion screws 38 threaded through suitable openings provided in the upper portions of supporting member 15, is disposed in magnetic relationship with the upper ends of cores 33 so as to be attracted to the cores when coils 34 of the electromagnet are energized. The electromagnet L may be provided in the usual manner with armature operated contacts comprising a stationary contact element 47 carried by a supporting bracket 15 and a movable contact element 48 carried by a dependent member 49 attached to armature supporting member 37 and arranged to be moved into and out of engagement with contact element 47 according as armature 36 is in its attracted or released position, respectively. It is, of course, obvious that by varying the arrangement of the parts 47 and 48 the contacts formed thereby may be arranged to be open or closed, respectively, according as armature 36 is in its attracted or released position.

Armature supporting member 37 also carries at its opposite end a finger 40 to which is secured locking dog 32, the arrangement being such that when electromagnet L is deenergized, dog 32 rotates armature 36 counterclockwise (as viewed in Fig. 2) about trunnions 38 to a position away from cores 33 with the dog 32 being positioned in the path of shoulder 31, but that when electromagnet L is energized, armature 36 is attracted toward cores 33 so that dog 32 is rotated clockwise about trunnions 38 to a position clear of the path of shoulder 31. As will be made clear hereinafter, the movement of dog 32 to a position clear of shoulder 31 in response to energization of electromagnet L may be restricted at times by cooperating dog and segment elements providing the positive force-down features for the locking device, but such movement will be completed when the dog and segment elements are moved out of cooperating relationship. The cooperating dog and segment force-down elements as shown comprise a projection in the form of a lug or pin 44 provided on locking segment 30, and a cooperating depressor member 41 mounted on finger 40 and provided with a cammed surface adapted to engage and be driven underneath pin 44. Depressor member 41 as shown (see Figs. 6 and 7) has a cam arm 45 carried at the lower end of a supporting leg 45a of member 41, and is beveled at one end so that when dog 32 is positioned clear of shoulder 31 (as shown in Figs. 6 and 7) movement of pin 44 past dog 32 will force the beveled surface of arm 45 downwardly to draw down dog 32 into the path of shoulder 31. The parts are preferably so proportioned that when pin 44 rides on the upper horizontal surface of arm 45, dog 32 is forced down to approximately one-half of the depth of shoulder 31. When dog 32 occupies its full down position (illustrated in Fig. 2) the dog rests on the cut-away portion of segment 30 and the horizontal surface of arm 45 is then disposed underneath pin 44. With dog 32 in its full down position and member 41 and pin 44 in cooperating relationship any movement of dog 32 upwardly will be restricted by arm 45 engaging pin 44 to limit the upward movement of dog 32 so that the dog is positioned at half the depth of shoulder 31, and cannot be operated clear of the shoulder unless pin 44 is moved out of cooperat-

ing relationship with arm 45, or conversely arm 45 is moved out of cooperating relationship with pin 44.

The movement of pin 44 with relation to arm 45 is effected in normal operation of the locking device, as will be made clear hereinafter, while movement of arm 45 with respect to pin 44 is required for emergency operation of the locking device and in accordance with my invention is attained by pivoting member 41 on finger 40, and by providing means operable to swing member 41 to a position where cam arm 45 is out of cooperating relation with pin 44. Depressor member 41 as shown in Figs. 6 and 7 is slotted to receive finger 40 to which it is pivotally attached by a pin 42 passing through aligned openings provided in finger 40 and the bifurcated portion of member 41. As can be seen in Fig. 6, member 41 is pivoted eccentrically so that the weight of the member causes it to be biased in a clockwise direction about pin 42 with cam arm 45 normally occupying a position in which it is disposed for cooperating relationship with pin 44. The bottom of the slot diagonally opposite pin 42 is relieved at an angle (see Fig. 6) which permits member 41 to be rotated counterclockwise about pin 42 to a position in which arm 45 clears pin 44, and in this position of member 41 the relieved bottom of the slot in member 41 will bear against the bottom of finger 40. A pin 43, as shown in Figs. 6 and 7 preferably is pressed tightly into an opening formed in member 41 and projects at an angle to the axis of finger 40. Pin 43 is adapted to cooperate with an operating member of an emergency release hereinafter described to rotate member 41 about pin 42 to a position in which arm 45 clears pin 44, and then subsequently to lift finger 40 so that dog 32 is withdrawn from the path of shoulder 31.

The emergency release means provided for swinging member 41 about its pivot 42 comprises a manually operable plunger 65 slidably mounted in a supporting bracket 66 secured to the rear of face plate 10 with the plunger projecting outwardly through an opening formed in the face plate. The plunger 65 is provided at its outer end with a knob 68 and is biased to an outermost position as by a coil spring 69 confined between an upturned leg of bracket 66 and a spring collar 70 secured to plunger 65 as by a pin 71. The portion of plunger 65 projecting outwardly from face plate 10 is slotted adjacent to the face plate to receive a thin ribbon 73 of metal which has its ends fastened together as by the usual car seal. The sealed ribbon will function as a telltale to indicate that an operation of plunger 65 has been effected, and will prevent such an operation until the ribbon is broken and removed from the slot to permit plunger 65 to be moved inwardly. Member 65 carries at its extreme inner end an operating member 72 disposed normally clear of pin 43 of depressor member 41, but movable when plunger 65 is depressed to engage pin 43 to cause rotation of depressor member 41 about its pivot pin 42 so that cam arm 45 is operated clear of pin 44, and the relieved portion of the slot of member 41 bears against finger 40 to force that finger upwardly, thereby moving dog 32 entirely clear of shoulder 31 of segment 30.

The locking device also is provided in the customary manner with indication means for indicating the condition of locking imposed by the device upon the operation of shaft 47. This means as shown in Fig. 2 comprises an arcuate member 50 pivoted to rotate about a pin 51 and

visible through a window 52 provided in an opening 53 formed in face plate 10. Member 50 is operated by an operating rod 54 fastened to locking dog 32 with the arrangement being such that when locking dog 32 is in its lowermost position in locking engagement with segment 30, arcuate member 50 rotates to its lowermost position, but when locking dog 32 is operated to or above the previously mentioned position in which the dog is withdrawn to one-half of the depth of shoulder 31, rod 54 drives member 50 to an upper position in which a legend, such as "Unlocked," is visible through window 52. The pin 51 about which member 50 rotates is supported by a member 55 which in turn is supported from elements 56 secured to or formed integrally on face plate 10 and disposed on either side of dog 32 to provide restraining surfaces which prevent lateral movement of the dog.

The parts of the locking device hereinbefore described are suitably enclosed by a housing 60 formed to cover both sides, the rear and the top of the device and provided with an opening 61 through which a staple 62 fastened to face plate 10 projects to provide a hasp for a padlock (not shown) for locking housing 60 to the other parts of the lock device. The housing 60 when removed provides access to the working parts of the locking device.

The lock device hereinbefore described will operate in the following manner: With handle 18 in its extreme left-hand position, as viewed in Fig. 1, the handle will be retained in this position by the natural bias of the parts including the weight of locking member 27 supported from crank arm 24. In this position of the parts, locking member 27 is positioned in opening 29 of lockable member 28 so that this position of handle 18 corresponds to the locking condition of the device, and pin 44 carried by segment 30 is disposed immediately above but out of engagement with cam arm 45 of depressor member 41. With the parts in the positions described and electromagnet L deenergized, dog 32 will rest against the notched or cut-away portion of segment 30 so that the dog is disposed in the path of movement of shoulder 31, arcuate member 50 will be rotated as shown in Fig. 2 to its lowermost position in which the legend "Unlocked" is obscured, while another legend "Locked" may be provided on the member 50 to be visible in this condition of the apparatus, or as shown, the latter legend may be omitted from member 50 so that no legend is visible at this time through the window.

I will now assume that electromagnet L becomes energized in response to current supplied to coils 34 over an energizing circuit (not shown). When this happens, armature 36 is attracted toward pole pieces 33 to rotate armature supporting member 37 about its trunnion screws 38, thereby causing dog 32 to lift away from the notched portion of segment 30. Upward movement of dog 32 is restricted however at this time since cam arm 45 of depressor member 41 will engage pin 44 carried by segment 30. As previously mentioned, the parts of the indication means are so proportioned that the limited upward movement of dog 32 permitted at this time will be sufficient to cause rod 54 to rotate member 50 to the position in which the legend "Unlocked" is visible through window 52. This will indicate to the operator that handle 18 can be operated to the extreme right-hand position, and I will assume that the operator grasps handle 18 and swings the handle toward its right-hand extreme position. The operation of handle 18 away from its extreme left-

hand position results in pin 44 moving to the left (as viewed in Fig. 1) out of engagement with cam arm 45, thereby removing the restraint upon the upward movement of dog 32 so that armature 36 is attracted to its full down position to snap dog 32 out of the path of movement of shoulder 31. This operation will take place immediately upon pin 44 disengaging from arm 45 and will result in dog 32 being lifted away from the path of shoulder 31 prior to the time that the shoulder reaches a position of engagement with dog 32, with the result that handle 18 can be swung without interruption to its extreme right-hand position to cause operation of the contacts operated by the drum type controller and to lift locking member 27 out of opening 29 of lockable member 28. With handle 18 in its right-hand position, lockable member 28 is free to move so that this position of handle 18 corresponds to the unlocking condition of the device. The handle will be retained in this position by spring 63 engaging a notch 64 formed in the lower portion of segment 30 (see Fig. 1). It is, of course, obvious that if the operator should attempt to move handle 18 from its left-hand to its right-hand position at a time that dog 32 is disposed in the path of shoulder 31, handle 18 will freely move toward its right-hand position until shoulder 31 abuts against locking dog 32 at which position further movement of handle 18 is prevented. The locking dog 32 and shoulder 31 therefore cooperate to prevent movement of handle 18 to its right-hand position unless dog 32 is withdrawn from the path of movement of shoulder 31 and dog 32 accordingly is positioned in locking relationship with segment 30, or is out of such locking relationship, according as the dog is or is not disposed in the path of shoulder 31.

In this normal operation of handle 18 effective when dog 32 is operated by the associated dog operating mechanism, it is to be noted that the operator will not attempt to move handle 18 until after the "Unlocked" indication is exhibited through window 52, and that after such indication is displayed handle 18 may be operated without interruption to its extreme right-hand position by the operator throwing the handle to its unlocking (right-hand) position. In order to unlock member 28, therefore, the operator is merely required to move handle 18 to its unlocking (right-hand) position after receiving the "Unlocked" indication.

When handle 18 is operated to its right-hand or unlocking position, electromagnet L may be deenergized or not but in either case operation of handle 18 back to its left-hand locking position will result in dog 32 assuming its locking relationship with segment 30. Restoration of handle 18 to its left-hand position may be effected only when lockable member 28 is positioned so that locking member 27 can enter opening 29, and assuming that this condition obtains, handle 18 may then be restored to its left-hand position by the operator. If electromagnet L is deenergized at the time handle 18 is restored to its left-hand position, dog 32 will be resting against the upper portion of segment 30 so that when shoulder 31 moves past dog 32, the dog will drop down to rest against the cutaway portion of the segment and will be positioned for engaging shoulder 31. If, however, electromagnet L is energized when handle 18 is restored to its left-hand position, or if with electromagnet L deenergized dog 32 should stick in its clear position, then dog 32 will not drop when shoulder 31 moves beyond the dog, but the dog will be forced down into locking relation-

ship with segment 30 by pin 44 engaging cam arm 45 to drive that arm downwardly and under pin 44. This action will usually be sufficient to correct any sticking action of dog 32 with electromagnet L deenergized and generally will result in such cases in dog 32 dropping to its full down position. In the case where electromagnet L is energized, however, the dog 32 will remain in its position half withdrawn from shoulder 31 established by arm 45 engaging pin 44, until electromagnet L becomes deenergized so that dog 32 drops to its full down position. The "Unlocked" legend of member 50 will of course become obscured when dog 32 operates to its full down position, and this will inform the operator that dog 32 is in locking relationship with segment 30.

Under the conditions just described operation of handle 18 from its locking to its unlocking position will be prevented at all times except when electromagnet L is energized, and it may be possible that operation of the handle is required at a time when the electromagnet L cannot be energized as, for example, due to some failure of the parts of its energizing circuit. Under these conditions the emergency release means embodying my invention provides means effective after operation to permit the operator to unlock member 28 merely by moving handle 18 to its unlocking (right-hand) position. Assuming that operation of handle 18 from its left-hand to its right-hand position is desired at a time when electromagnet L cannot be energized to operate locking dog 32, the operator will first break and remove ribbon 73 from the slot of plunger 65 so that the plunger is free to be moved inwardly. The operator will next depress plunger 65 to move operating rod 72 inwardly into engagement with pin 43 pressed into depressor member 41. This will rotate member 41 about its pivot 42, arm 45 will be swung out of cooperating relationship with pin 44, and the relieved bottom of the slot in member 41 will bear against finger 40, thereby forcing the finger upwardly to drive dog 32 out of the path of shoulder 31. The upward movement of dog 32 at this time will not be restrained by arm 45 engaging pin 44, consequently the dog 32 will be operated to its uppermost position in which armature 36 is swung into a position corresponding to its attracted position with respect to cores 33, and the armature and dog will therefore occupy the positions corresponding to those established when electromagnet L is energized and pin 44 is moved clear of cam 45. This operation of dog 32 out of locking relationship with segment 30 will result in operation of member 50 by rod 54 so that the legend "Unlocked" is displayed through window 52. The operator will hold plunger 65 depressed, and will move handle 18 to its extreme right-hand unlocking position. Plunger 65 may now be released and when the operator does this, plunger 65 will operate to its outermost position in response to the bias of spring 69, and operating rod 72 will disengage from pin 43 so that member 41 will swing back to its biased normal position in which arm 45 is disposed for engaging pin 44 when handle 18 is restored to its locking position. Dog 32 will also drop into rest against the upper portion of segment 30 and the parts will therefore assume the condition which obtains when electromagnet L becomes deenergized after handle 18 is operated to its unlocking position with electromagnet L energized. With the parts in the condition described, the handle 18 may be restored to its left-hand position by the operator in the manner explained in detail hereinbe-

fore in connection with the description of the normal operation of the locking device.

It is to be noted that the emergency release means embodying my invention provides for unlocking member 28 merely by operating handle 18 to its unlocking position after the "Unlocked" indication is displayed through window 52. The operation of the locking device under emergency conditions of operation is therefore identical with the operation under normal conditions, in that in either case the operator will not attempt to move handle 18 until after an "Unlock" indication is exhibited, and after such indication is received the operator obtains an unlock merely by moving handle 18 without interruption to its right-hand position. In the case of emergency operation, the "Unlock" indication is provided by the operator depressing plunger 65 to its extreme innermost position before actuating handle 18, so that a condition is established which is maintained by the operator without change while operating handle 18 to unlock member 28.

From the foregoing description it is readily apparent that I have provided an emergency release means effective to operate a locking dog from its locking to its unlocking position during the interval that a depressor member provided on the locking dog is disposed in a position to engage a positive draw-down projection provided on the locking segment. The emergency release means is arranged to move the depressor member out of the path of engagement with the draw-down projection and then to withdraw the locking dog from its locking position. The arrangement therefore provides means which makes it possible to incorporate both a positive draw-down of the locking dog and an emergency release in a locking device.

The emergency release means embodying my invention is highly advantageous for use with a locking device having positive force-down features for a locking dog, in that it provides the same type of operation of the operating member under both normal and emergency conditions of operation. The operator may therefore obtain an unlock merely by moving the operating member after receiving an "Unlock" indication, and therefore the emergency operation is exactly the same as normal operation, except for the usual depression of the emergency release plunger required to establish the emergency operation.

Although I have herein shown and described but one form of emergency release for locking devices embodying my invention, it is understood that various changes and modifications may be made therein within the scope of the appended claims without departing from the spirit and scope of my invention.

Having thus described my invention, what I claim is:

1. In a locking device, in combination with a locking dog operable into and out of locking engagement with an operating member movable between a first and a second extreme position only when said locking dog is out of its locking engagement, two cooperating elements comprising an element on said operating member and an element on said locking dog, said two elements being positioned in cooperating relationship in said first extreme position of said operating member with one of said two elements projecting into and obstructing the path traveled by the other element when said locking dog is operated out of locking engagement with said operating member, and means for moving one

of said two elements relative to the other whereby to remove said two elements from cooperating relationship and permit said dog to be operated out of locking relationship when said operating member occupies its said first extreme position.

2. In a locking device, a locking dog operable into and out of locking relationship with a locking segment operable between a first and a second extreme position only when said locking dog is out of locking relationship with said segment, two cooperating elements comprising a first element on said locking segment and a second element on said locking dog, said first element being positioned in said first extreme position of said locking segment to project into and obstruct the path traveled by said second element when said locking dog is operated out of its said locking relationship, and means operable with said locking segment stationary in its said first extreme position for moving one of said two elements relative to and clear of the other whereby to permit said dog to be operated out of its said locking relationship with said locking segment.

3. The combination according to claim 2 in which said one element movable relative to the other is pivoted for rotation into and out of cooperating relationship with said other element, and said means for moving said one element rotates said one element out of cooperating relationship with said other element.

4. The combination according to claim 3 in which said means rotating said one element out of cooperating relationship with said other element also effects operation of said locking dog out of locking relationship with said locking segment.

5. In a locking device, in combination with a locking segment movable between two extreme positions and a locking dog operable into and out of locking engagement with said locking segment for respectively preventing and permitting movement of said segment from one extreme position to the other, a projection on said segment, a cooperating depressor member pivotally connected with said locking dog and having a cammed surface adapted to be driven underneath said projection for drawing down said locking dog into locking engagement with said segment, and means operable for rotating said depressor member out of cooperating relationship with said projection whereby to permit said locking dog to be forced out of locking engagement with said segment.

6. In a locking device, in combination with a locking segment movable between two extreme positions and a locking dog operable into and out of locking engagement with said locking segment for respectively preventing and permitting movement of said segment from one extreme position to the other, a projection on said segment, a cooperating depressor member pivotally connected with said locking dog and having a cammed surface adapted to be driven underneath said projection for drawing down said locking dog into locking engagement with said segment, and means operable for rotating said depressor member out of cooperating relationship with said projection and for subsequently forcing said locking dog out of locking engagement with said segment.

7. In a locking device having means positively forcing down a locking dog which cooperates with a shoulder formed on a locking element operatively connected with an operating member

for preventing movement of said operating member from a first to a second extreme position unless said locking dog is operated to a position clear of the path of movement of said shoulder; said force down means including a projection on said locking member for cooperating with means carried by said locking dog and effective in a given portion of the stroke of said operating member to draw down said locking dog into the path of movement of said shoulder, the combination with such projection of cooperating means comprising a member pivotally mounted on said locking dog for rotation into and out of a position of engagement with said projection and biased into said engaging position, and means operable for rotating said member against its bias out of said engaging position to permit said locking dog to be forced clear of said shoulder.

8. In a locking device, in combination with a locking segment movable between a first and a second position, and a locking dog operable into and out of locking engagement with said locking segment for respectively preventing and permitting movement of said segment from its said first to its said second position, a projection on said segment, a cooperating depressor member pivotally connected with said locking dog and biased to a position to engage said projection when said segment is moved into its said first position whereby a portion of said depressor member is driven beneath said projection in said first position of said segment, and means for rotating said depressor member clear of said projection to per-

mit operation of said locking dog out of locking engagement with said segment in its said first position.

9. In a locking device, in combination with a locking segment movable between a first and a second position, and a locking dog operable into and out of locking engagement with said locking segment for respectively preventing and permitting movement of said segment from its said first to its said second position, a projection on said segment, a cooperating depressor member pivotally connected with said locking dog and biased to a position to engage said projection when said segment is moved into its said first position whereby a portion of said depressor member is driven beneath said projection in said first position of said segment, and means for rotating said depressor member clear of said projection and for operating said locking dog out of locking engagement with said segment in its said first position.

ISAIAH W. VENSEL.
